PLLC(57) **CLAIM**

The ornamental design for a face vibromassage apparatus.

DESCRIPTION

FIG. 1 is a right perspective view of new design for a face vibromassage apparatus as shown in the drawings;

FIG. 2 is a front elevation view;

FIG. 3 is a rear elevation view;

FIG. 4 is a left side view;

FIG. 5 is a right side view;

FIG. 6 is a top plan view;

FIG. 7 is a bottom plan view; and,

FIG. 8 is a left perspective view.
